William Koch,
BY *W. Koch*

ATTORNEY

UNITED STATES PATENT OFFICE.

WILLIAM KOCH, OF NEW YORK, N. Y.

QUILTING-MACHINE.

SPECIFICATION forming part of Letters Patent No. 375,552, dated December 27, 1887.

Application filed December 26, 1885. Serial No. 186,681. (No model.)

To all whom it may concern:

Be it known that I, WILLIAM KOCH, of the city, county, and State of New York, have invented a certain new and useful Improvement 5 in Quilting-Machines, of which I declare the following to be a full, clear, and exact description, reference being had to the accompanying drawings, forming a part thereof.

This invention is in the nature of an improvement in quilting-machines; and the invention consists in a quilting-machine with three or more needle-bars constructed and combined so that the spaces between all or any two of the bars may be varied, as with 15 greater particularity is hereinafter shown, described, and claimed.

In the accompanying sheet of drawings, Figure 1 represents a cross-section of the needle-bars of my machine; Fig. 2, a plan or top view 20 of same; Fig. 3, detail views of sleeves. Fig. 4 is also a plan view of the needle-bars separated by sleeves of unequal lengths.

Similar letters of reference indicate like parts in the several figures.

This invention relates particularly to quilting machines which have three or more rows of needles fixed to a corresponding number of needle-bars, for the purpose of quilting designs of given patterns on the fabrics exposed 25 to the action of the needles. Now it is obvious that if the several rows of needles are of uniform distances apart, or if the spaces between any two or all of the rows remain the same, the designs to be quilted will, under 30 such circumstances, be always of the same character and design, without deviation or variation, and it is to break up and change this uniformity of design that I construct my quilt-

ing-machine with its needle-bars A arranged parallel with each other and connected by bolts 40 b. Now, as these bars have each fixed to them needles c, it is plain that the order, arrangement, or design of the stitches may be changed by increasing or decreasing the space a between these needle-bars; and to that end, by the 45 use of suitable nuts applied to the bolts b and removable sleeves B, of different lengths, which may be placed on the bolts b and between the bars A, as shown in Fig. 1, the spaces a between the bars may be made to vary throughout the series, so that, the relative position of the bars being altered, the designs stitched by the needles will vary accordingly, and an almost infinite variety of stitching or quilting be produced by this simple adjustment of the 50 55 needle-bars.

Of course many means may be adopted for effecting this adjustment, and I do not therefore desire to confine myself to any one or more ways of doing it, and I only show the 50 sleeve method in the drawings for illustration and as an example of one of the simplest methods.

Having now described my invention, what I claim as new, and desire to secure by Letters 65 Patent, is—

In a quilting-machine, the combination, with three or more parallel needle-bars connected by a series of bolts, b, of sets of sleeves B, of different lengths, adapted to be slipped on said bolts, whereby the spaces between the bars may be varied.

WILLIAM KOCH.

In presence of—

D. A. CARPENTER,
L. MONTEMAR.
